UNITED STATES PATENT OFFICE.

WILLIAM B. FOLGER, OF CINCINNATI, OHIO.

WATER-HEATER.

SPECIFICATION forming part of Letters Patent No. 680,769, dated August 20, 1901.

Application filed May 31, 1895. Serial No. 551,090. (No model.)

To all whom it may concern:

Be it known that I, WILLIAM B. FOLGER, a citizen of the United States, and a resident of Cincinnati, in the county of Hamilton and 5 State of Ohio, have invented certain new and useful Improvements in Water-Heaters, of which the following is a specification.

My invention is designed for domestic purposes, and especially for heating water for 10 baths, stationary washstands, &c.

Its object is to provide a compact, durable, and easily-managed device so arranged that the water will be quickly raised to the desired temperature, the temperature regulated by 15 controlling the flow of water, and accidents from carelessness, ignorance of the laws governing the evaporation or heating of water, or other natural causes avoided.

The invention will be first fully described 20 in connection with the accompanying drawings, and then particularly referred to and pointed out in the claims.

Referring to the drawings, in which like parts are indicated by similar reference-letters wherever they occur throughout the various views, Figure 1 is an end elevation of the heater and its connections and support, except the housings, which are cut away and shown in transverse vertical section. Fig. 2 25 is a side elevation of the same with the housings shown in vertical longitudinal section. Fig. 3 is a transverse vertical sectional view of the heater with the housings removed, the section being taken on line $x-x$ of Fig. 2 looking to the right. Fig. 4 is a plan view of the device with the housings left off. Fig. 5 is a detailed view, upon an enlarged scale, of the air-drum interposed in the supply leading to the water-heating coils. Fig. 6 is a plan view 30 of the lower course of coils; Fig. 7, a plan view of the heater, the housings and water-coils being removed. Fig. 8 is a central longitudinal vertical section of the same, taken through line $y-y$ of Fig. 7. Fig. 9 is a longitudinal vertical sectional view of the gas-controlling cock, upon an enlarged scale, taken 35 through line $z-z$ of Fig. 10. Fig. 10 is a plan view of the water and gas controlling cocks. Fig. 11 is a longitudinal vertical sectional view 40 of the water-controlling cock, taken through line $v-v$ of Fig. 10.

The supporting-stand of the heater is a rectangular angle-frame A, supported upon legs A', which have inwardly-projecting webs or flanges a , upon which the frame A rests. The 55 upper ends of the legs overlap the angles of the frame and are secured to it by screws passing through their laterally-projecting wings.

Upon the inwardly-projecting web of the 60 angle-frame A is supported the gas-burner. This consists of the transverse pipe B, the ends of which are secured to the angle-frame A. Into this pipe, upon opposite sides, are secured a number of parallel perforated tubes 65 b, which are closed at their ends. This burner is of ordinary construction, and any well-known form of burner may be substituted in its place.

The lower series of heating-coils is composed 70 of clusters of small pipes c, the ends of which are secured in funnel-shaped receivers C. The receivers at one end are secured in a manifold C' and at the opposite end in semi-circular unions C². This lower series of coils 75 is supported above the gas-burner upon brackets or legs c', the lower ends of which are secured to the frame A, and the upper ends have inwardly-projecting flanges to pass under the manifold C' and unions C². The upper series 80 of coils D, of which there are four, are alike in construction, except that the first and third coils are shorter than the second and fourth of the series. At one end these coils are coupled to plain manifolds d and at the opposite 85 end to the manifolds d', which have screw-threaded nipples d², projecting down from the alternate corners of each series to engage screw-threaded openings in the manifold below each one of the series, so as to establish 90 communication between the terminal of one series and the initial tube of the series below it, the nipple d² of the lower coil of the series D being tapped into the perforation in the manifold C' of the lower series, and the nipples 95 and their engaging necks in the alternate series of coils being so arranged that the pipes in each of the upper series of coils are above the openings between the pipes below, so as to establish a free circulation of heat 100 around all the coils. The arrangement of the manifold d as shown in Fig. 2—that is, hav-

ing the intermediate ones coming under the pipes instead of under the manifolds above them—is for the same purpose.

The coupling E for the water-supply pipe 5 and F for the gas-supply are secured in brackets e and f, which are secured underneath the frame A, E' being the pipe leading from the water-main and F' the pipe leading from the gas-main. The couplings E and F, which are, 10 in fact, cases for the valve or cocks f' and e', pass through the frame and are connected on the inside, the one with the heater-pipe B and the other with the upright water-supply pipe e', which leads to the upper series of water- 15 coils D and connects to the lower branch of the air drum or chamber E². The opposite branch of the chamber E² is connected to the manifold d' by a short branch pipe e².

The heating-pipes D and c are, in order to 20 secure rapid heating, preferably made of copper tubes, and where there is a heavy pressure of water these are liable to crack or split when the full supply is turned on, owing to the "water-hammer" caused by compressed air 25 in the pipes. In order to overcome this objection, I have provided the upper end of the vertical pipe e' with the drum E², thus providing a chamber above the flow of the water leading to the coils. This being made much 30 heavier than the water-pipes and being above the upper series of coils receives the air which would otherwise pass through the coils, and the air being compressed by the water flowing through insures a steady flow of water and 35 prevents all jarring and hammering.

To prevent the coils from being injured by turning on the gas when there is no water or an insufficient supply of water in the pipes, I have coupled the water and gas supply cocks 40 together. The plugs e³ and f' have formed integral with them intermeshing cogged segments e⁴ and f², and the plug e³ has also a handle e⁵, by turning which in one direction or the other both cocks are simultaneously 45 opened or closed. The leading edge of the passage or way through the cock e³ is beveled off, so that when the handle is turned to turn on the water and gas it gives the water a lead and the water-supply is turned into the pipes 50 before the burner is lighted. The plug f' is perforated from the top down to the gas-passage, as clearly seen in Fig. 9, and upon the top of the plug is secured a supplemental gas-cock f³, which has a jet-tube f⁴, forming part 55 of its plug f⁵. The passage leading to the plug f⁵ is always open from the gas-main, and when it is desired to light the burner the cock f³ is turned and the gas lighted from the jet f⁴. When this jet is lighted and the 60 handle e⁵ is turned to turn on the water-supply, the tube or jet-pipe will pass over the top of the burner and ignite the gas passing through its perforations. This jet-pipe f⁴ is so arranged that when the supply of gas and 65 water are both cut off the discharge-orifice of the jet-tube will be slightly within the outer case or housing of the heater and nearly op-

posite the vertical water-supply pipe e', so that in very cold weather the gas from the jet-pipe f⁴ may be left burning and will produce heat enough to prevent any freezing of the water in the heater or in the water-pipe leading to it. I have also provided the water-supply cock e³ with a supplemental valve, the stem e⁶ of which is screw-threaded and 70 tapped into a perforation in the cock e³. The lower portion of the stem, being a plain cylinder and passing across the waterway in the cock e³, regulates the supply of water passing to the heater. Thus by turning the 75 hand-wheel e⁷ to retract the lower shaft of the stem e⁶ and draw it out of the waterway through the plug or cock e³ a full supply of water will be turned on, and when turned in the opposite direction to close or partially 80 close the waterway, as clearly seen in Fig. 11, the supply of water to the heater is limited. By this means the supply of water to the heater may be regulated as desired when the full pressure of gas is turned on, and of 85 course the more limited the supply of water that is passed through the heater the higher will be its temperature. The supplemental valve is so arranged that at no time can the supply of water be turned entirely off, so that 90 while the gas is burning there is always a supply of water passing through the coils.

The discharge-pipe G for the heated water is connected to one branch of the T-coupling g. To the opposite branch of this coupling 95 is connected the faucet H. The opposite end of the pipe G is connected to a plain coupling g', which is secured to the opposite end of the frame A. The outer end of the coupling is closed by a screw-plug g². The purpose of this arrangement is to adapt the faucet to either end of the heater, which may be done by placing the faucet in one end and the plug in the opposite end, or, if it is desired to employ two faucets, one for the bath-tub and the other for the stationary washstand, the plug g² is removed and the other faucet substituted in its place. The vertical branch of the union g is connected to the coupling g³, which has a union g⁴, which connects to the terminal branch c³ of the lower coil C. The seat of the valve in the faucet H is scored or notched, so that it cannot be entirely closed off. The purpose of this is to prevent accident from explosion should the 105 water-supply be closed off from this faucet while the gas is burning. The faucet H is not necessary when there is only one discharge for the heated water, and a plain pipe would answer all purposes, as the flow of water would be entirely regulated by the compound water-supply valve above described; but when the heater is to be used to supply a bath-tub and stationary washstand it is obvious that two faucets would be required, so 110 that the water might be discharged from one or the other faucet, as desired.

In order to retain the heat from the burner around the coils, I have provided two hous-

ings J and K, both of which may be made of light sheet metal. The inner housing J incloses the water-coils. Its top is perforated to pass the air-chamber E², and the top walls 5 flare out near the center, leaving an opening leading to the upper chamber between the housings J and K. This inner housing is slipped over the coil and rests upon the inclined walls of the brackets c'. The outer 10 casing K, which I prefer to make of Russia iron, either plain or nickel-plated, as desired, slips over the inner housing, leaving a chamber between the two, and is supported upon the top edge of the supporting-legs A'. One 15 side wall of the housing K has an opening to permit the jet-tube b⁴ to swing in over the burner, the opening being protected by an escutcheon k. The upper arched top of the housing K is perforated to allow the heated 20 air to escape, which, together with the radiation from the surface of the housing K, serves as a heater for the bath-room.

The series of coils are put together by first 25 inserting the nipple of the lower or cluster coil in the coupling g⁴ and turning the cluster series around until the nipple is screwed tight in the coupling. Each of the series of coils above are in succession connected in the same manner, and then the short branch 30 pipe E², the opposite ends of which have one a right-hand and the other a left-hand thread, is screwed in place, connecting the upper coil with the water-main. By this means the water-coils can be readily put together, and the 35 connections between them support the coils in the proper position; but it is obvious that other well-known means may be employed to connect the coils of the upper series with the lower cluster-coil. It is also obvious that 40 other well-known forms of water-coils may be used above my lower heating-coil C and also that my arrangement of connected valves for supplying gas and water may be employed with a different arrangement of heating-coils. 45 I have, however, shown the best means known to me of embodying my invention in a completed structure; but I do not desire to be limited to the specific details shown, as the heater may be changed in mechanical details 50 without departing from the spirit or scope of my invention.

What I claim as new, and desire to secure by Letters Patent, is—

1. In a heater of the character described, 55 the combination of the burner, the lower water-coil formed in clusters, the pipes connected at opposite ends to common unions or

return-bends which compel the water to travel in a sinuous path from its initial to its terminal union, a series of coils of larger 60 pipes arranged above the cluster-coils, a pipe to supply water from the main or other source of supply to the initial pipe of the upper coil, a gas-supply for the burner, and regulating-cocks interposed between the water and gas 65 supply and the water-coils and burner, substantially as shown and described.

2. The combination of the upper series of coils of tubes with the lower coil formed of clusters of smaller tubes connected to common unions at each end and with a burner below the lower coil, whereby the water received from the upper series of coils is divided by the tubes and subjected to a high degree of heat by the flame passing between 75 and around the clusters, substantially as shown and described.

3. The combination in a water-heater of the heating-pipes arranged in series one above the other, the connected manifolds or returns 80 for the ends of the pipes, each manifold at one end of each series having a screw-threaded neck at one end and a screw-threaded nipple at the opposite end to connect the manifolds and support the pipes, substantially as 85 shown and described.

4. The combination in a water-heater of a series of heating-coils arranged one above the other, the water-supply pipe connected to the top coil of the series, and the air-chamber 90 connected to the top of the supply-pipe above the branch leading to the top coil, substantially as shown and described.

5. The combination of the heating-coils, a water-supply leading thereto, a valve interposed in the water-supply pipe to turn the water on or off from the coils, a supplemental regulating-valve arranged in the plug of the main valve to regulate the quantity of water passing to the coils without moving the main 100 valve, a gas-burner beneath the coils, a gas-supply pipe leading to the burner, a valve in the gas-supply pipe and connections between the gas-valve and the main valve of the water-pipe by which the gas-valve and the main 105 water-valve may simultaneously be opened and closed, and the supplemental valve may be regulated independently, substantially as shown and described.

WILLIAM B. FOLGER.
